UNITED STATES PATENT OFFICE.

JOSEPH ESCHELBACHER, OF NEW YORK, N. Y.

DESIGN FOR A BADGE-FRAME.

SPECIFICATION forming part of Design No. 33,156, dated September 4, 1900.

Application filed July 11, 1900. Serial No. 23,280. Term of patent 3½ years.

To all whom it may concern:

Be it known that I, JOSEPH ESCHELBACHER, a citizen of the United States, residing at New York, borough of Manhattan, State of New York, have invented and produced a new and original Design for Badge-Frames, of which the following is a specification, reference being had to the accompanying drawing, forming part thereof, and which shows a badge-frame embodying my new design in front elevation.

As shown in the drawing, the leading or material features of my design consist of a ring-shaped open portion A, an oblong bar portion B above the same, and two circular open ornaments C C arranged between the

upper edge of the ring-shaped portion A and the adjacent edge of the bar portion B, the same being located at a suitable distance inwardly and away from the ends of the bar portion B. The ends of the bar portion B are concaved, as shown.

What I claim is—

The design for a badge-frame, as shown and described.

In testimony that I claim the foregoing as my invention I have signed my name in presence of two subscribing witnesses.

JOSEPH ESCHELBACHER.

Witnesses:

K. MACMILLAN,
I. S. HARRIS.
